UNITED STATES PATENT OFFICE.

HENRY R. WORTHINGTON, OF DUNNFIELD, NEW JERSEY.

SIGNALING APPARATUS.

1,238,975.

Specification of Letters Patent.

Patented Sept. 4, 1917.

Application filed February 26, 1910. Serial No. 546,093.

To all whom it may concern:

Be it known that I, HENRY R. WORTHINGTON, a citizen of the United States, residing at Dunnfield, in the county of Warren and 5 State of New Jersey, have invented certain new and useful Improvements in Signaling Apparatus, of which the following is a specification.

My invention relates to that class of apparatus which is employed at sea and at 10 signaling stations and light houses for the purpose of communicating information to others in the vicinity.

One of the objects of my invention is to 15 provide means which in times of fog, rain or snow, will enable officers in command of ships to give definite information to every one in their vicinity as to the position of their ships and the direction in which they 20 are moving. Although my invention is adapted to such use, it is equally as well adapted for use in connection with light houses and signaling stations and at all places where, in times of fog and under conditions when the ordinary signal light 25 cannot be distinguished, it is important to communicate information to others in the vicinity.

At such times it is the usual practice on 30 board of vessels, to blow stationary steam whistles and fog horns at frequent intervals for the purpose of advising approaching ships as far as possible of their location. But in the absence of any knowledge of the direction in which the approaching ships are 35 proceeding, collisions frequently ensue.

By means of my invention these difficulties are overcome and the officers of the two ships equipped with apparatus embodying 40 the principles of my invention may be promptly advised, if the two ships approach within signaling distance of each other, as to the relative directions in which the respective ships are moving and where they are 45 located with respect to each other, thus enabling the courses to be changed to avoid collision. And under similar conditions of weather, a light house equipped with a signaling device embodying my invention can 50 communicate its exact location with respect to that ship's location.

Another object of the invention will appear hereinafter, the novel combinations of elements being set forth in the appended 55 claims.

Referring to the accompanying drawing,

The figure is a plan view, partly diagrammatical, of apparatus embodying my invention.

I prefer to mount in the bow of each ship 60 a transmitting device comprising a whistle in a megaphone, and comprising also mechanism for oscillating the megaphone across the bow of the ship through about 180 degrees and intermittently operating the 65 whistle. It should be understood that the megaphone, if desired, could be arranged to revolve on a given axis instead of to oscillate. In the form of transmitting apparatus shown in the drawing, on a base plate or support 1 are mounted all of the parts except 70 the battery 2 and the manual switch 3, which may be located wherever desired. For instance, the switch 3 may be placed in the pilot house or on the bridge. 75

A small electric motor 4 which in this instance is controlled by the switch 5 and the rheostat 6, is connected by the shaft 7 and the worm 8 to the gear wheel 9 which is rotatably connected to the base plate in a horizontal position. At 10, near the periphery of the gear 9, is connected a pitman or link 11, the other end of which is connected at 12 to the gear 13, which in turn meshes with the gear 14. Connected with the gear 14 so as 80 to move therewith, is a megaphone 15 containing at its inner end a whistle 16 which may be an electrically-operated air whistle, or a steam whistle, the valve of which is controlled by an electro-magnet 22. 85

Connected to the gear 9 so as to rotate therewith, is a pinion 30, which meshes with a comparatively large gear 29. At 27 is an electric switch which is normally open but may be closed by the cam 28 when the gear 95 29 moves to a predetermined position. The speed of the motor 4 and the proportions of the worm 8 and the gears 9, 30 and 29, may be such that the gear 29 will rotate once in approximately one minute, and the cam 28 100 may be of such length that the switch 27 will be closed for about five seconds in every minute. The number of times these signals should be blown in any unit of time would be a matter of maritime regulation. In the 105 case of light houses, the duration and frequency of the blasts would differ in different locations and be noted on the charts as are differences in the duration and frequency of the light flashes. Whatever the timing of 110 the rotation of the gear 29 is, I prefer to arrange the apparatus so that the switch 27

will be closed while the megaphone 15 is oscillating from port to starboard.

It should be noted that in this instance the circuits and connections controlled by the switch 27 are such that when the lever 19 is on contact 31 and the switch 27 is closed by the cam 28, the circuit will be completed through the electrically-operated whistle or through the magnet 22 controlling the valve 10 of a steam or air whistle. This circuit may be traced from the battery 2 through a conductor 21, electro-magnet 22, conductor 23, lever 19, contact 31, conductor 32, switch 27 and conductors 33, 26, back to the battery 2.

If for any reason it is desired to blow the whistle more frequently, this can be done by providing a semi-circular cam 17 on the lower side of the gear 9 to close the switch 18 for five seconds during every 10 seconds. In such case, the whistle would be blown each time the megaphone moved across the bow of the ship from port to starboard. To effect this more frequent operation of the whistle, the lever 19 is moved off the contact 31 on to the contact 20 so that whenever the switch 18 is closed a circuit will be completed from the battery 2 through conductor 21, magnet 22, conductor 23, lever 19, contact 20, conductor 24, switch 18 and conductors 25, 26 back to the battery 2.

In the drawing the full lines represent the positions of the parts when the mouth of the megaphone is directed over the bow 25 of the ship, and the dotted lines represent the positions of some of the parts including the megaphone when the latter is in its extreme starboard position. It should be noted that although the motor 4 and disk 40 9 rotate continuously in one direction, the link 11 is pulled back and forth to effect an oscillation of the megaphone from side to side across the bow of the ship. I prefer this construction to insure the operation of 45 the whistle only when the megaphone is directed in a predetermined manner which will be understood by the officers of other ships.

It will be found that where the whistle is 50 operated while the megaphone is moving through an arc of 180 degrees, to a person at a distance the sound will be at its greatest intensity when the mouth of the megaphone is pointed directly toward him, and that 55 through all other portions of the arc the sound is greatly decreased in volume although audible throughout its entire length to an extent about equal to the volume of sound which the same whistle would emit 60 at the same distance if unattached to a megaphone. Thus, it will be seen, that when a ship equipped with my signaling device is moving head on toward one listening to the signals, the sound will be first low, then become loud and again low, with the loudest 65

portion at substantially the middle of the blast of the whistle. When the ship is moving at an angle toward the observer, the loudest part of the blast of the whistle will be either nearer the beginning or end of the blast, according to whether the ship is moving toward the right-hand side or left-hand side of the observer. If the ship is moving directly away from the observer, the blast will be lower at the middle part thereof, and if moving at an angle away from the observer, the lowest part of the blast will be either toward the beginning or end of the blast, according to the direction in which the ship is traveling. When a ship is equipped with a device such as described, an observer may know definitely in which direction the ship is traveling by hearing the blast.

While I have illustrated and described the preferred form of construction of my invention, I do not desire to be limited to the precise details set forth, but desire to avail myself of such variations and changes as come within the scope of the appended claims.

Having thus described my invention, what I claim and desire to have protected by Letters Patent of the United States, is:

1. In a signaling device, the combination 95 of a sound producing device movably mounted, means for oscillating said device through a predetermined arc of a circle, and means for operating said device while moving in one direction of its oscillation and maintaining the device silent while moving in the other direction of its oscillation.

2. In signaling apparatus, the combination with a sound-producing device, of a megaphone for directing the sound from such device in a predetermined direction, and means for oscillating said sound-producing device and megaphone through a wide angle and operating said sound-producing device during such oscillation only for a predetermined arc of movement and while moving in only one direction of its oscillatory movement.

3. In signaling apparatus for ships, the combination with a sound-producing device, 115 of a megaphone associated therewith, automatic means for moving said megaphone and sound-producing device through a wide angle having a definite relation to the longitudinal median line of the ship, and mechanism for effecting the continuous operation of the sound-producing device while the megaphone is moving in a predetermined direction over a predetermined arc of said angle.

4. In a signaling apparatus, the combination with a megaphone, of a sound producing device in connection with the megaphone, means for oscillating said megaphone over a wide angle, and mechanism for effect-

ing the operation of said sound producing device while the megaphone is moving in only one direction of its oscillation, and preventing its operation during movement in 5 the other direction of its oscillation.

5. In signaling apparatus, the combination with a sound-producing device, of electric apparatus for operating said device, a megaphone mounted for oscillatory movement and associated with said sound-producing device, and automatic mechanism for controlling said electric operating apparatus to effect the sounding of said sound-producing device by means of said automatic mechanism while the megaphone is directed in 10 a predetermined direction and moving angularly.

6. In signaling apparatus, the combination with a sound producing device, of a sound reflector associated therewith, apparatus for oscillating said sound producing device and reflector through a wide angle, and a device for effecting the operation of said sound producing device when moving 25 angularly in one direction but not when returning.

7. In signaling apparatus, the combination with a whistle, of a sound reflector associated therewith, automatic means for oscillating said reflector through a wide angle, and automatic means for operating said whistle only when said reflector moves angularly in one of its directions of movement.

8. In signaling apparatus, the combination with a megaphone, of a whistle associated therewith, electric means for operating said whistle, mechanism for oscillating said megaphone through approximately 180 degrees, and circuits and connections for 40 controlling the operation of said whistle by means of said oscillating mechanism while the megaphone is moving angularly through approximately 180 degrees in one direction but not when returning.

45 9. In signaling apparatus, the combination with a sound producing device, of a sound reflector associated therewith, means for oscillating said reflector, automatic means for operating said sound producing 50 device through said oscillating means only when the reflector is being moved angularly in one of its directions of movement, and electric circuits and connections for changing the arc of movement of the reflector over 55 which the sound producing device is operated.

10. In signaling apparatus, the combination with a megaphone, of a whistle associated therewith, automatic mechanism for 60 continuously oscillating said megaphone through a wide angle, means for controlling said whistle by means of said oscillating mechanism while the megaphone is being moved over one of its paths but not when 65 returning, and connections for varying the

frequency at which the whistle is blown but retaining the predetermined direction of movement of the megaphone while the whistle is sounded.

11. In an apparatus employing sound for 70 the purpose of signaling, the combination with means for concentrating said sound in one direction, means for oscillating the line of said concentrated sound through a wide angle, a sound-producing device, and mechanism for effecting the operation of said sound-producing device while said sound-concentrating means is moving from left to right or from right to left, but not when moving in the opposite direction. 80

12. In signaling apparatus, the combination with a whistle, of a megaphone associated with said whistle, means for oscillating said megaphone through an arc of about 180 degrees, mechanism for effecting the operation of said whistle while the megaphone is being moved from right to left or from left to right, but not when being moved in the opposite direction. 85

13. In combination with a ship, of an apparatus for employing sound for the purpose of signaling, means for concentrating said sound in one direction, means for moving the line of said concentrated sound through a predetermined arc of a circle, said 90 arc bearing a fixed relation to the longitudinal axis of said ship, and mechanism for effecting the operation of said signaling apparatus only when the sound-concentrating means is being moved angularly in a predetermined direction. 100

14. In an apparatus employing sound for the purpose of signaling, the combination of means for concentrating said sound in one direction, means for moving the line of said concentrated sound through a predetermined arc of a circle and back again continuously, said arc bearing a fixed relation to the points of the compass, and mechanism for effecting a continuous operation of said 105 signaling apparatus when the sound-concentrating means is moving over said predetermined arc in one direction but preventing its operation during its return movement to initial position. 110

15. In an apparatus employing sound for the purpose of signaling, the combination of a megaphone for concentrating said sound, means whereby the line of said concentration is made to sweep through a predetermined arc of a circle and back again continuously, and mechanism for effecting the sounding of said signaling apparatus when said megaphone is moved over said predetermined arc of a circle in one of the 115 directions of movement and preventing the sounding of said signaling apparatus when said megaphone is returning over said predetermined arc of a circle. 120

16. In an apparatus employing sound for 130

the purpose of signaling, the combination with a whistle, of a megaphone, apparatus for moving said megaphone through a horizontal plane in the arc of a circle and back again continuously, and means whereby said whistle is caused to sound only when said megaphone is being moved over a predetermined arc of said circle in one of its directions of movement and not in the other.

10 17. In an apparatus employing sound for the purpose of signaling, the combination of a megaphone and a whistle, and means whereby said whistle is sounded while the megaphone is moving over a predetermined 15 arc in a predetermined direction and prevented from being sounded while moving in the opposite direction.

18. In a signaling apparatus by means of sound, the combination of sound producing 20 mechanism, means whereby said sound is concentrated in one direction, and mechanism for effecting the operation of said sound-producing mechanism while the sound-concentrating means is moving over a wide 25 angle in a predetermined direction and not in the opposite direction.

19. In signaling apparatus, the combination with a whistle, of a reflector associated therewith, a gear connected to said reflector, 30 a second gear meshing with said first-mentioned gear, a driving gear, and a pitman connecting said driving gear with said second-named gear to cause the first and second gears and the reflector to oscillate while 35 said driving gear continuously rotates.

20. In signaling apparatus, the combination with an electric whistle, of a sound reflector associated therewith, a driving gear, an electric switch operated by said 40 driving gear, a gear connected to said sound reflector, an intermediate gear meshing with said sound reflector gear, and a pitman connecting said intermediate gear and said driving gear to effect the oscillation of the 45 sound reflector while said driving gear continuously rotates.

21. In signaling apparatus, the combination with a whistle, of a sound reflector associated therewith, a driving gear, intermediate mechanism between said driving gear and said sound reflector to effect the oscillation of the latter while the driving gear continuously rotates, and means associated with said driving gear for effecting the 50 operation of said whistle only when said sound reflector is being moved over a predetermined arc of a circle in a predetermined direction.

22. In a signaling apparatus, the combination with a whistle, of a sound reflector associated therewith, an electro-magnet for operating said whistle, a driving device, intermediate mechanism between said driving de-

vice and said reflector for effecting the oscillation of said reflector through a wide angle 65 while said driving device moves continuously in the same direction, switching mechanism associated with said driving device for effecting the operation of said electro-magnet and the sounding of said whistle 70 while the sound reflector is moving in one direction over its arc of movement but not while returning, reduction gearing, and switch mechanism associated with said reduction gearing to effect the operation of 75 said whistle at less frequent intervals but while said sound reflector is moving in the aforesaid predetermined direction over the said predetermined arc of movement.

23. In a signal device, the combination of 80 a ship, a megaphone mounted on said ship, means for oscillating said megaphone through an angle having a definite relation to the ship, a sound producing device mounted in and carried by said megaphone, 85 and means for operating said sound producing device while moving in one direction of its oscillation and maintaining it silent when moving in the other direction of its oscillatory movement.

90 24. In a signal device, the combination of a ship, a megaphone movably mounted at the bow of the ship, means adapted to oscillate said megaphone through an angle of substantially 180°, said angle being bisected by the longitudinal median line of the ship, a sound producing device mounted in the megaphone, and means for operating the sound producing device while traveling in only one direction of its oscillatory movement.

95 25. In a signaling device, the combination of a supporting object, a megaphone movably mounted on said object, a sound producing device mounted in said megaphone, means moving said megaphone and device in one direction through a definite angle which is bisected by a certain line passing through said object and bringing the megaphone and device into position again to be moved through said angle in said direction, and means operating said sound producing device while passing through said angle in said direction, and maintaining the device inoperative when not passing through said angle in said direction.

110 In testimony whereof I have signed my name to this specification, in the presence of two subscribing witnesses, on this 11th day of February A. D. 1910.
